FIREARM

Hans Erik Eklund, Malmo, Sweden, assignor to
 Aktiebolaget J. C. Ljungman, Malmo, Sweden,
 a corporation of Sweden

Application September 17, 1943, Serial No. 502,806
 In Sweden September 12, 1942

4 Claims. (Cl. 42—3)

The invention refers to an arrangement in automatic or semi-automatic firearms with a barrel provided with a gas outtake, wherein a breech block and a movable member adapted to actuate said breech block directly from a loading mechanism, to which the driving gases are conveyed from said gas outtake of said barrel through a pipe conduit or the like, and wherein the opposite ends of said pipe conduit and of said movable member of the loading mechanism are formed into a working cylinder and into a driving piston cooperating therewith and having a rectilinear path for said movable member of the loading mechanism.

The present invention has for its object to bring about a simplification and improvement of the weapons of a similar type as hitherto known.

Other objects and advantages of the invention will appear as the following description is read in connection with the accompanying drawing.

In the drawing:

Fig. 1 is a vertical longitudinal section of a portion of a small firearm in accordance with the invention. Included in the drawing are only those parts which are necessary to elucidate the invention.

Fig. 2 is a portion of the members according to Fig. 1 in separated position.

Fig. 3 is a modification of the embodiment of Figs. 1 and 2.

Figs. 4 and 5 represent details pertaining to the embodiments according to Figs. 1 and 3 respectively, but viewed here from above relatively to the former figures.

In the drawing, 1 designates the gunstock of the firearm, 2 the barrel, 3 the cartridge chamber, 4 the bore, 5 the mechanism casing of the firearm, 6 the cartridge magazine, 7 the breech block, 8 the movable member adapted to actuate the breech block, said movable member 8 being constituted here by the so-called lock piece consisting of a locking means for the breech block when the arm is prepared for firing, 9 denotes the firing pin which is slidably mounted in the breech block 7. The pipe conduit 10 constitutes the passage adapted to convey the powder gases from the barrel to the loading mechanism.

According to Figs. 1 and 2, the pipe conduit 10 opens at one end thereof at the loading mechanism and particularly into the mechanism casing 5 which is here formed into a rigid cylinder 11, while the lock piece 8 is formed at its end directed towards the pipe conduit 10 into a movable piston 12 cooperating with the cylinder 11 and adapted to be operated by the powder gases. Fig.

1 shows the piston 12 and the cylinder 11 telescoped into each other, and Fig. 2 shows these members separated in part at least. The pipe conduit 10 is here adapted to be displaced in its longitudinal direction within the casing 5.

After a shot has been fired, the powder gases act upon the piston 12 and throw the lock piece 8 back to the right in Fig. 1, the lock piece 8 then entraining the breech block 7 which latter entrains the cartridge case which is ejected. At the same time another cartridge will be fed up from the magazine 6, and when the lock piece 8 then by aid of the spring 18 returns forwardly, it again brings the breech block 7 along with it, the breech block 7 being thus caused to move the cartridge in a known manner into the cartridge chamber 3 while being itself locked by the lock piece 8 when the latter has reached its extreme position of advancement that is to say the position shown in Fig. 1. The loading mechanism, which has been here only indicated with respect to its action, is not entirely illustrated in the drawing, in the first place because it is previously known and, secondly, does not in itself form any object of this invention.

Fig. 3, in difference from Figs. 1 and 2, illustrates the pipe conduit 10 as opening into the casing 5, but with the end portion of the pipe conduit 10 formed into a rigid piston 13 cooperating with the end portion of the lock piece 8 taking the form of a movable cylinder 14. In spite of this reversal of the conditions, the effect is obviously the same. In Fig. 3 the casing is furthermore provided, round the end portion of the piston 13, with an annular groove 15, which in order to provide a more effective closure between the piston 13 and the cylinder 14 is adapted to receive at least a portion of the end of the cylinder 14 directed toward the pipe conduit 10.

Fig. 4 shows the arrangement according to Figs. 1 and 2 as viewed from above, and Fig. 5 shows the arrangements according to Fig. 3 as viewed in a similar way. In Fig. 4 the end surface 16 of the piston 12 and the edge portion 17 of the cylinder are bevelled off obliquely, whereby the powder gases will, at the movement of the piston 12 from the cylinder 11, obtain a first outlet upwardly in Fig. 4, before the hollow of the whole cylinder is uncovered to deflect the powder gases. Hereby facilities are provided to lead the powder gases in a certain direction, so that they will not interfere with the possibility of the marksman to see the breech sight. Fig. 5 shows a modification of the bevelled portion 19 which

here only comprises a portion of the edge of the cylinder.

The gas outtake from the barrel 2 is of a known type. It comprises in Fig. 1 a member 19 surrounding the barrel 2 and being connected to the barrel 2 by shrinking. The pipe conduit 10 is screwed with its end into the member 19 and a channel 20 in the barrel 2 and in the member 19 connects the bore 4 with the pipe conduit 10.

The piston 12 and the cylinder 14 may be in one piece with the movable member 8 or they may be of separate parts, which are shrunk or screwed together.

According to the invention the stroke of the movable member 8 is of a greater length than the length of the piston and the cylinder when they are telescoped together whereby on bringing them apart they uncover between them a direct outlet to the atmosphere for the driving powder gases.

From the foregoing it will be evident that with a firearm according to the invention the movable member 8 will be propelled from the end of the pipe conduit 10 as a ball from a weapon, that the pressure from the powder gases acts on the movable member 8 a short distance only of the stroke of said member 8, and that the smoke from the powder gases does not disturb the marksman.

The invention is susceptible of various changes in its form, proportions and minor details of construction and the right is herein reserved to make such changes as properly fall within the scope of the appended claims.

Having described the invention, what I claim is:

1. A firearm including a barrel having an outtake for the powder gases, a loading mechanism comprising a breech block and a movable member having a rectilinear path and being adapted directly to actuate said breech block, and a pipe conduit leading from said gas outtake on the barrel of said movable member of the loading mechanism, the opposed ends of said pipe conduit and of said movable member of the loading mechanism being formed into a working cylinder and a driving piston cooperating therewith, the end surface of said driving piston facing said working cylinder being provided with a bevelled portion in order to convey the escaping driving gases therethrough in a predetermined direction, said working cylinder and said driving piston being of such a small length relatively to each other that that one of them which is movable with the movable member of the loading mechanism leaves the other behind it on having performed a portion of its stroke thereby uncovering a direct outlet to the atmosphere for the driving powder gases.

2. A firearm including a barrel having an outtake for the powder gases, a loading mechanism comprising a breech block and a movable member having a rectilinear path and being adapted directly to actuate said breech block, and a pipe conduit leading from said gas outtake on the barrel to said movable member of the loading mechanism, the opposed ends of said pipe conduit and

of said movable member of the loading mechanism being formed into a working cylinder and a driving piston cooperating therewith, at least a portion of one of the opposed end surfaces of said pipe conduit and said movable member being provided with a bevelled portion in order to convey the escaping driving gases therethrough in a predetermined direction, said working cylinder and said driving piston being of such a small length relatively to each other that that one of them which is movable with the movable member of the loading mechanism leaves the other behind it on having performed a portion of its stroke thereby uncovering a direct outlet to the atmosphere for the driving powder gases.

3. A firearm including a barrel having an outtake for the powder gases, a loading mechanism comprising a breech block and a movable member having a rectilinear path and being adapted directly to actuate said breech block, and a pipe conduit leading from said gas outtake on the barrel to said movable member of the loading mechanism, the opposed ends of said pipe conduit and of said movable member of the loading mechanism being formed into a working cylinder and a driving piston cooperating therewith, at least a portion of one of the opposed end surfaces of said pipe conduit and said movable member being provided with a cut-away portion for conveying the escaping driving gases therethrough in a predetermined direction, said working cylinder and said driving piston being of such small length relatively to each other that that one of them which is movable with the movable member of the loading mechanism leaves the other behind it on having performed a portion of its stroke thereby uncovering a direct outlet to the atmosphere for the driving powder gases.

4. A firearm including a barrel having an outtake for the powder gases, a loading mechanism comprising a breech block and a movable member having a rectilinear path and being adapted directly to actuate said breech block, and a pipe conduit leading from said gas outtake on the barrel to said movable member of the loading mechanism, the opposed ends of said pipe conduit and of said movable member of the loading mechanism being formed into a working cylinder and a driving piston cooperating therewith, said working cylinder and said driving piston being of such a small length relatively to each other that that one of them which is movable with the movable member of the loading mechanism leaves the other behind it on having performed a portion of its stroke, the opposed ends of said working cylinder and said driving piston forming guide faces constructed and arranged to conduct the driving powder gases out from said working cylinder directly to the atmosphere in a predetermined direction, said pipe conduit with its end opposed to said movable member of the loading mechanism being located at the rear end of said barrel, the inside diameter of said working cylinder being larger than the inside diameter of said pipe conduit.

HANS ERIK EKLUND.
